GRILLE

Robert T. Bogan, Jr., 3620 High St. NE.,
Albuquerque, N. Mex. 87107

Filed Oct. 17, 1968, Ser. No. 14,036

Term of patent 14 years

Int. Cl. D25—01

U.S. Cl. D13—1

FIG. 1

FIG. 3

FIG. 1 is a front elevation of a portion of a grille embodying my new design, a rear elevation thereof being the same in appearance;

FIG. 2 is a fragmentary horizontal section, taken along line 2—2 of FIG. 1; and

FIG. 3 is a fragmentary vertical section, taken along line 3—3 of FIG. 1.

I claim:

The ornamental design for a grille, as shown and described.
